UNITED STATES PATENT OFFICE.

EDWIN TAYLOR, OF BROOKLYN, NEW YORK, ASSIGNOR TO TAYLOR LABORATORIES, INC., OF NEW YORK, N. Y., A CORPORATION OF NEW YORK.

TREATMENT OF ORGANIC MATERIAL.

Original application filed March 11, 1920, Serial No. 364,980. Divided and this application filed June 17, 1924. Serial No. 720,522.

My invention relates to improvements in the treatment of organic material, and more particularly to the treatment of cellular or fibrous organic material such as cellulose in the form of cotton or otherwise. This application is a division of my prior application Serial No. 364,980, filed March 11, 1920. The main object of this invention is to provide an improved method of treating such organic material whereby the same may be obtained in a finely divided state in a more efficient and economical manner. Further and more specific objects, features and advantages will more clearly appear from the detailed description given below.

In carrying out my invention I dissolve the organic material in a suitable solvent and then atomize the solution, so to speak, and then remove solvent constituents from the material by the aid of electrolytic action. I will illustrate the invention by describing the preferred treatment of cellulose material such as cotton. As solvent I prefer to use a solution of zinc chloride or cupro-ammonia, the latter prepared by dissolving hydrated cupric oxide in strong ammonia water.

After solution is complete the viscous mass is allowed to stand for about 24 hours, during which time it becomes much more fluid and may be forced through a filter by means of pressure. A fine sand bed on top of a layer of nitro-cotton, which in turn is supported by a fine wire screen is quite satisfactory. When desired the solutions are now concentrated by centrifugal action.

The colloidal solution of cellulose is then preferably treated in an apparatus like that shown in the accompanying drawing which forms a part of this specification and which illustrates more or less diagrammatically a section of an apparatus adapted for the purpose.

Referring to the drawing, a closed tank 10 is supplied with filling means 8, a pipe 9, for admission of pressure, and a nozzle or nozzles 12 provided with an orifice 4 extending through the tank wall preferably at the bottom. Below 10 is a second covered tank 20, containing dilute acid at the bottom and furnished with an overlapping end or compartment 52, above the acid level. The nozzle or nozzles 12, extend through the top of

20 to a point near the central line of compartment 52. Extending through the end 55 wall of compartment 52, and at right angles to 12, is a nozzle or nozzle 2 adapted to be supplied with compressed air or other gas, the whole constituting an atomizing arrangement in compartment 52. A metallic 60 belt 21 of any desired length and width and driven by a roller 25 exterior to tank 20 and supported by guide rolls 26—26'—26" enters tank 20 near the top at its rearward end, passes over roller 26 and downwardly 65 across the open end of compartment 52, until under the level of the acid in tank 20. The belt then passes under second guide roll 26', and longitudinally through the acid until 70 near the end of the tank where it passes down under another guide roll 26" and thence at an angle out of the acid through an aperture 59 in the end wall of 20 and over the driving roll 25, situated several feet beyond 20. This belt is provided with a contact shoe 28 carrying an electrical connection 29, and in use the belt becomes an anode. Running lengthwise of tank 20 near the bottom is a metallic plate 31, of any width with its forward end 31' upturned and provided 75 with a conductor 32 causing it to become a cathode on passing a proper electric current. A wide thin stream or curtain of acid water 54 is caused to flow continuously down that portion of the belt opposite compartment 52, 80 and with the run of the belt, by means of a slotted pipe 55 running across the top of the tank. Beyond tank 20 is another tank 50 across which runs a second slotted pipe 58 so situated that clean water may be driven 85 through it with the run of the belt, thereby dislodging any material adhering to the belt and preventing this wash water from running down the belt into tank 20. The acid water in 20 is used to supply pipe 55, 90 through intermittently operated auxiliary tanks (not shown) so that the current may not ground itself through the circulating system. An outlet pipe 33 serves to remove 95 any gas injected into or developed in the 100 apparatus.

In operation tank 10 is filled with any desired organic material dissolved in a metal containing solvent and pressure applied. In this case dilute solutions are preferable to viscous, concentrated ones on ac-

count of the finer particles produced by the atomizers. The belt 21 is started running, in the direction shown by arrows and a curtain of acid water flowed across its descending face by pipe 55. Compressed air or other gas is driven through nozzle 2 across the descending stream of dissolved organic material and the resulting spray 53 driven against the descending acid water curtain whereby the fine spray particles are immediately covered by a protecting film which prevents them from adhering to one another, successive fresh acid continually meeting the incoming particles. The line of impact of the spray 53 on the water curtain should be as narrow as possible and for this reason the orifices 4 of the nozzles 12 and also of the nozzles 2 should be narrow slots in preference to round holes. Owing to the contact of the acid water with the belt and with the liquid in tank 20 the fine particles of organic matter are in an electric field from the time of impact and in consequence seek to adhere to the anode or belt 21, the particles which do not immediately adhere do so later during their travel between the electrodes, they being carried along by the flow of liquid caused by the descent of the acid water and the directional flow given it by the upturned end 31' of the cathode 31 and held in suspension until they are pulled to the anode by the electrical current.

During their passage through the electrolytic tank or cell the current passes through the particles of cellulose solution causing, by electrolytic action, the copper or metal of the solvent to be deposited on the cathode, freeing the ammonia or chlorine as the case may be, and the thus purified cellulose to be more firmly deposited on the traveling anode in finely divided condition. In this way the solvent constituents are removed from the cellulose or the like electrolytically. The time required for deposition of the metal and release of the gaseous constituent is small, due to the large surface exposed to electrolytic action by the fine state of division and the much thinner wall or membrane through which the solvent constituents are obliged to pass. The belt with its adhering load of organic material now passes out of the acid water through the opening 59 in tank 20 and towards driving roll 25. As the particles pass the opening in pipe 58 they are swept from the belt by the water driven from said opening and together with the water fall into wash-tank 50. After washing, the finely divided material is ready for any subsequent operations or uses. Owing to the atomizing and to the great shrinkage in volume (approximately 80%) in drying (which may be done by placing the powder in a container and passing carbon tetrochlor-

ride, acetone or other dehydrating agent therethrough), the product may be obtained in a state of microscopical fineness. It is particularly adapted for insulating packing material, as an absorbent, or after nitration, for explosive purposes.

As to the process in general, the utmost care should be exercised to avoid all dust and dirt. The solutions must be carefully filtered and dirt kept out afterward. All the apparatus should be closed in wherever possible. The water employed for making up the solutions should be distilled or at any rate contain a minimum of mineral salts and should be free from carbonic acid gas if a fine filament or a perfectly transparent product is desired.

The strength of the acid employed is a variable factor depending upon whether the cellulose, etc., is subjected to the electrolyzing current during the forming or whether the formed material must be transported some distance before coming under its influence. It is best found by experiment for any particular case although I have never used above $\frac{3}{4}$ of 1% and from $\frac{1}{4}$ to $\frac{1}{2}\%$ is generally sufficient of sulphuric acid. I prefer to use nitric acid as its ultimate product under electrolysis is always ammonia. The bath may be kept to strength by the simple addition of nitric acid, the ammonia released from the organic solution or formed by electrolysis being readily drawn from the top of the tanks and directly recovered, and any residual acid easily removed from the cellulose, etc., by washing.

If silk material is used as raw material it may be dissolved in a solution of nickel ammonia formed by dissolving hydrated nickel oxide in 30% ammonia water.

The material produced by the above process or processes is in most cases capable of being again dissolved by solvents having the same constitution as those originally used and any trimmings, misshapen pieces, etc., may be redissolved and added to fresh solutions thereby reducing waste of raw or finished material.

While I have described my improvements in great detail and with respect to preferred embodiments thereof, I do not desire to be limited to such details or forms, since many changes and modifications may be made and the invention embodied in widely different forms without departing from the spirit and scope of the invention in its broader aspects; hence I desire to cover all modifications and forms coming within the language or scope of any one or more of the appended claims.

What I claim as new and desire to secure by Letters Patent, is:

1. The method of treating organic material which consists in treating the same with a solvent to put the material in solu-

tion, spraying the solution to finely divide it, and removing solvent constituents therefrom electrolytically.

2. The method of treating cellular or fibrous organic material which consists in dissolving the material in solvent therefor, spraying the solution on a moving carrier to deposit the solution on the carrier in divided condition and passing the carrier 10 through an electrolytic field to remove solvent constituents from the material by electrolytic action.

3. The method of treating cellulosic material which consists in dissolving the material in a suitable solvent, spraying the solution to subdivide it into small particles and subjecting the latter to electrolytic action to remove solvent constituents therefrom.

4. The method of treating cellulosic material which consists in dissolving the material in a suitable solvent, spraying the solution onto a moving carrier and passing the material on the carrier through an electrolyte in an electrolytic cell to remove solvent 25 constituents therefrom.

5. The method of treating cellulosic material which consists in dissolving the material in a suitable solvent, spraying the solution to subdivide it into small particles and 30 subjecting the latter to electrolytic action to remove solvent constituents therefrom and

removing the purified particles from the carrier by spraying.

6. The method of treating cellulosic material which consists in dissolving the material in a suitable solvent containing a metal, spraying the solution to subdivide it into small particles and subjecting the latter to electrolytic action to remove solvent constituents therefrom. 35

7. The method of treating cellulosic material which consists in dissolving the material in a suitable solvent containing a metal, spraying the solution to subdivide it into small particles and subjecting the latter to electrolytic action to remove solvent constituents therefrom, and removing the purified particles from the carrier by spraying. 40

8. The method of treating cellular or fibrous organic material which consists in dissolving the material in solvent therefor, spraying the solution on a moving carrier to deposit the solution on the carrier in divided condition and passing the carrier through 45 an electrolytic field to remove solvent constituents from the material by electrolytic action, and removing the purified particles from the carrier by spraying. 50

In testimony whereof I have signed my name to this specification.

EDWIN TAYLOR.
